UNITED STATES PATENT OFFICE.

NELS HOFSTAD, OF CHICAGO, ILLINOIS.

PRESSURE-RESPONSIVE DEVICE FOR THERMOSTATS.

1,215,803.

Specification of Letters Patent. Patented Feb. 13, 1917.

Application filed April 10, 1916. Serial No. 90,074.

To all whom it may concern:

Be it known that I, NELS HOFSTAD, a citizen of the United States, residing at Chicago, in the county of Cook and State of Illinois, have invented certain new and useful Improvements in Pressure-Responsive Devices for Thermostats, of which the following is a specification.

My invention relates to pressure responsive device for thermostats and has especial reference to devices of this character for controlling valves, or the like.

One of the salient objects of my invention is to improve the structure of such devices and more particularly to provide more durable, efficient and reliable pressure responsive means for moving the valve operating parts.

Another object of my invention is to provide a protecting device for the sensitive pressure-responsive means, to protect it against injury by puncture, from meddling persons and whereby its movement is more positively transmitted to a part to be moved thereby.

Other and further objects of my invention will become readily apparent, to persons skilled in the art, from a consideration of the following description when taken in conjunction with the drawings, wherein:—

Figure 1 is a plan view of a device embodying my improvement.

Fig. 2 is a section thereof taken on line 2—2 of Fig. 1.

Fig. 3 is a transverse section taken on line 3—3 of Fig. 2.

In all the views the same reference characters are employed to indicate similar parts.

My invention is especially applicable to and useful in connection with a somewhat similar device fully set forth and disclosed in United States Letters Patent No. 1,109,993 granted September 8th, 1914.

In describing my improvements of such instruments, therefore, I shall refer only to such parts of the entire structure as are necessary to a complete description and disclosure of its operation. It is to be understood, however, that my invention is not to be limited in its use to the specific structure with which it is shown to be associated as it may be used in many other environments, being limited only by the scope of the appended claim.

In the operation of the thermostatic de-

vice it becomes necessary to move the valve-moving motor-arm 5 upon its pivot 6 to move the three way air valve 7 in response to temperature conditions which act on the thermostatic bar 8 to produce the desired movement. The frame 9, carrying the apparatus, is mounted upon a plaster back 10 which is secured to the wall or other support, by nails or screws, that pass through the perforations 11.

The specific invention sought to be protected in this application consists of the air responsive device 12 which is a metallic bellows diaphragm structure consisting of a plurality of diaphragms specifically the diaphragms 13 and 14, suitably secured together at their peripheral edges, the latter being centrally perforated for a nipple 15, carrying a central perforation 16. The frame 9 is provided with an aperture 17, which is screw threaded for the nipple 15 but is somewhat deeper than necessary for the accommodation of the nipple and which is flanked by a communicating duct, or opening 18, which in turn communicates with a chamber surrounding the needle valve 19, through the port of which, air is admitted through the duct 18 and from thence into the chamber between the diaphragms 13 and 14, to expand the same. The diaphragms 13 and 14 are annularly corrugated and are necessarily made of relatively thin, flexible metal, sensitive to rough usage and liable to rupture when violently contacted by sharp pointed instruments, or the like. To protect the diaphragms from such resultant damage

from such or other causes I provide a cap, or covering 20, of relatively thick heavy material which consists of a disk 21 provided with a side flange 22 to hold it upon the diaphragm structure. This cap or cover 20 is sufficiently stiff to transmit the power produced by the expanding diaphragm structure 12 to the motor arm 5, that is normally in contact therewith. To further protect the diaphragm 13 I provide a relatively yielding soft cushion 23, such as a disk of fabric, such as muslin, contained between the inner surface of the cap 20 and the said diaphragms. This prevents unnecessary wear upon the diaphragm and acts as a cushion to protect it from injury from sudden impact producing movement.

The metallic diaphragm structure, which is the subject of my invention, may be easily

and quickly replaced in the frame of the thermostatic valve device; is not subject to leak by deterioration, as is the case with a rubber diaphragm as by the action of the oil that may come through with the compressed air that is admitted to the expansion chamber; is so constructed and arranged that all of the expansive effect produced by the air admitted thereto is communicable to 10 the part to be moved thereby and, therefore, it is economical in the use of air for producing a given result. It reduces the number of separable parts necessary for the structure, of the device as a whole, and is inclosed 15 in a protecting shield or cap which does not modify the sensitiveness of the expanding portions of the diaphragm and transmits the entire motion of the diaphragms to the part to be moved thereby. The cap 20 also 20 limits the effective movement of the dia-

phragm structure in one direction, as shown in the drawings.

Having described my invention, what I claim is:

A diaphragm structure comprising a plurality of expansible diaphragms connected together at their peripheries; a connection to a terminal diaphragm; a protecting cap substantially inclosing said diaphragms and movable with the other terminal diaphragm 25 of the series to transmit motion produced thereby, and a cushion disk of relatively soft material within said cap. 30

In testimony whereof I hereunto set my hand in the presence of two subscribing witnesses. 35

NELS HOFSTAD.
